UNITED STATES PATENT OFFICE.

GEORGE EDWARDS BJÖRMAN, OF PARIS, FRANCE.

APPARATUS FOR PERMANENT UNDULATION.

Application filed December 11, 1926, Serial No. 154,137, and in France November 16, 1926.

The present invention relates to apparatus for permanent undulation with aid of electricity and its object is to devise an apparatus superior to those known hitherto.

5 According to the invention use is made of a hair-curler provided with electric resistances for heating, the lock of hair being rolled on this curler and held thereon by means of a tie forming a protector.

10 Usually, the locks to be submitted to undulation are firstly rolled around of curlers and maintained by means of strings or otherwise, whereupon they are placed into the interior of a heating apparatus, tubular and 15 provided, for example, with an electric heating coil surrounding the chamber of vaporization of the apparatus.

A treatment of this kind is long and complicated.

20 According to the present invention, instead of introducing the curlers into heavy and voluminous apparatus, use is made of a special type of curler heated inwardly by inner resistances in the manner employed 25 already for the electric curling irons.

In order to maintain the lock on the curler, two pincers are utilized, formed by two rods articulated, the one on the other and pressed close by means of any suitable device; the 20 one of the pincers forms, moreover, the protector and carries, for this purpose, two soft plates of india rubber or the like rolled around each of the branches of the pincers, fixing, if applied against each other, the 25 curler by means of the other pincers, preventing thereby the lock from getting loose, concentrating the hair and protecting the scalp at the same time.

The apparatus constructed in this manner 30 constitutes, in comparison with apparatus utilized hitherto, a real progress, being much lighter and dispensing with the usual crown or collar suspended from the ceiling as well as with pincers, strings and so on.

The invention will be better understood with reference to the drawings appended showing, in the way of an example, one preferable executive form of the subject-matter of the invention.

35 Figure 1 shows the detail of the curler,
Figure 2 the upper pincers,
Figure 3 the lower pincers forming at the same time a tie and a protector, and
Figure 4 represents the apparatus after 40 rolling of the hair-lock and closing of the pincers.

The curler consists of a metal rod 1 preferably nickel-plated and provided inwardly with a resistance in the manner existing already in the electric curling irons.

60 At one extremity of the curler a head of ebonite or other insulating substance 4 is provided, carrying the usual terminals 5 for its connection to a prolongator 6.

A band of gauze 2 retained by asperities 65 or hooks 3 (obtained by simple cuts in the metal) serves to protect the hair-lock from direct contact with the metallic rod 1. According to the case, one or several layers of gauze—for example for treatment of white 70 hair—are rolled around the curler, the yellowing action of heat on white hair by heating too strongly not recommending itself.

The two utilized pincers can be of any 75 suitable type, for example of the one represented in Figure 2, comprising two metal branches 7 forming an articulation at 8 and pressed against each other by means of a ring 9.

The pincers could comprise two elastic 80 branches, arcuate and kept together by means of a small spring pivoting and forming a hook at its one extremity, such device needing no other means in order to keep closed the pincers, one single movement 85 being sufficient in order to close and to hook on the two branches.

The pincers could be also, as represented in Fig. 3, in form of fastening racks 10, with curved extremities 11, in shape of 90 spatulas in order to facilitate handling, similarly to the surgical instruments.

Independently of the type adopted, the lower pincers (Figure 3) carry, rolled on each of their branches, two flexible plates 12 95 of india rubber, leather or other material soft and resisting and operate to form a protector.

The upper pincers, on the contrary, (Figure 2) are bare.

100 In order to serve oneself with the apparatus, firstly the protector forming a tie 12 is placed in order to protect the long hair, and thereupon the hair-lock M is passed between the two branches 7 kept apart from the pincers. Now these branches are closed and fixed, as alluded to or otherwise, for example by a ring.

110 The lock being rolled on the curler and protected from direct contact with the same by the band of gauze, the lips 12 of the protector are raised and then maintained ap-

plied against each other by means of the second pair of pincers (Figure 2) kept close in the manner stated previously.

The soft plates 12 applied against each other retain and concentrate the heat, fix at the same time the curler, prevent the lock from getting loose and protect the long hair.

If the hair has been already undulated by permanent undulation, it will be frequently sufficient and preferable to undulate only the roots, the extremity of the lock M surpassing in this case freely between the lips 12 of the protector, as represented in Figure 4 and the said lock being hence only partly rolled around the curler.

This feature constitutes a very great advantage of the apparatus because avoiding a very rapid deterioration of hair by an excessive heating, which advantage cannot be realized with the other apparatus known hitherto.

Cotton stoppers 13 or better still, wedges of india rubber are utilized in order to raise the curler and to increase the protection of the scalp.

The invention is not limited to the single executional mode as described and permits the most different modifications without departing from the scope of the main invention idea.

What I claim is:—

1. In an apparatus for permanent undulation with aid of electricity, a metallic rod, an electric resistance therein, layers of gauze on said rod, plates of soft material to receive the hair-lock between them and the gauze, one pair of pincers to receive the free ends of said plates in order to fasten them, and

another pair of pincers to press their other extremities against each other after placing 40 of the lock between them and the rod, around of the latter.

2. In an apparatus for permanent undulation with aid of heat generated by an electric current, a metal rod, an electric resistance 45 within the same, terminals for the same, layers of gauze on said rod, plates of soft material, one pair of pincers for attachment thereto of said plates, and another pair of pincers for keeping applied against each 50 other said plates, and fastening means for the two branches of these pincers to keep them closed.

3. In an apparatus for permanent undulation with aid of heat generated by an electric current, a metal rod, an electric resistance within the same, terminals for the resistance, layers of gauze on said rod, means on said rod to maintain the said gauze applied against said rod, plates of soft material, one pair of pincers for attachment thereto of said plates, another pair of pincers for keeping applied against each other said plates, and fastening means for the two branches of said latter pincers to keep them 65 closed.

4. A heating element, presser plates, and means to arrange said presser plates in spaced relation to opposite sides of the heating element to hold strands of hair adjacent 70 said opposite sides of said heating element, and to releasably secure said presser plates in such position, said means comprising two pairs of pincers.

In witness whereof I affix my signature,
GEORGE EDWARDS BJÖRKMAN.
